INVENTOR

William Serviss
Per Brown Esq.

United States Patent Office.

WILLIAM SERVISS, OF SIDNEY, OHIO.

Letters Patent No. 72,688, dated December 24, 1867.

IMPROVEMENT IN MACHINE FOR MAKING RINGS.

The Schedule referred to in these Letters Patent and making part of the same.

TO ALL WHOM IT MAY CONCERN:

Be it known that I, WILLIAM SERVISS, of Sidney, in the county of Shelby, and State of Ohio, have invented certain new and useful Improvements in Apparatus for Making Rings; and I do hereby declare that the following is a full, clear, and exact description of the same, reference being had to the accompanying drawings, making a portion of this specification, in which—

Figure 1 is a side view of an apparatus constructed according to my invention.

Figure 2 is an end view and partial section of the same.

Figure 3 is a plan view of the same.

Figures 4 and 5 are detached views of rings made by means of the apparatus.

Similar letters of reference indicate corresponding parts in the several figures.

This invention is designed more especially for making the rings commonly employed for the handles of tin, sheet-iron, and copper-ware, and it consists in mandrels made interchangeable, and constructed with a hole near one end, in combination with a supporting-shaft furnished with a crank, whereby the wire may be readily bent into the required form, and whereby the apparatus is adapted for making rings of different shapes and sizes.

The invention further consists in the arrangement of the mandrel and shaft with reference to a grooved anvil, in such manner that the curved portions of the ring may, when required, be readily brought into finished shape with the hammer.

The invention further consists in a novel arrangement of flat-faced supplemental anvils, with reference to the anvil and the mandrel hereinbefore mentioned, whereby the straight portions of the class of rings referred to may be conveniently worked into proper form and position.

To enable others to understand the nature and construction of my invention, I will proceed to describe it with reference to the drawings.

A represents a solid standard, upon the upper end of which is formed the anvil B, the face or upper surface of which is made concave in its cross-section, as shown more fully in fig. 2, and formed with transverse semi-circular grooves, *a*, the purpose of which will be presently set forth. Projecting horizontally from one side of this anvil B are two flat-faced anvils, A* B*, one of which is larger than the other; and projecting in like manner from the opposite side of the main anvil B, is another flat-faced anvil, C*, of a still larger size than those marked A* B*, just mentioned. The office of these supplemental anvils A* B* C* is to enable the straight portions of rings designed for handles for sheet-metal ware to be brought into the required shape and position, as hereinafter further explained. Working through the standard A, just below the anvil B thereon, is a horizontal shaft, C, one end of which is provided with a crank, *b*, and the opposite end portion of which is made flat on one side, as shown at *c*, in fig. 2. Fitted upon this portion of the shaft C, so as to turn therewith, is a mandrel, D, which may be retained thereon by a nut, *a'*, and which, taken transversely, corresponds in shape and size with the interior of the ring designed to be formed upon it, and is provided at one end with a hole, *b'*. Inasmuch as the mandrel may be readily detached from the shaft, interchangeable mandrels of different sizes may be employed upon the same apparatus for making different kinds of rings.

In using the apparatus, the end of the wire from which the rings are made is inserted in the hole *b'* of the mandrel, which is then rotated by means of the crank *b*, and the wire is coiled thereon, which being done, the coils of the wire are divided transversely at or near the centre of the flat portion *c'* of the mandrel, when the rings are made straight or flattened at one side, as shown in figs. 4 and 5, and are then removed from the mandrel, each coil being separately brought into the form required in the finished ring by properly shaping its curved portions in the semicircular grooves *a* by means of a suitable hammer, and bringing the two ends of its flat portion in line and in contact with each other by hammering upon the flat faces of one of the supplemental anvils A* B* C*.

What I claim as my invention, and desire to secure by Letters Patent, is—

1. The interchangeable mandrels formed with a hole near one end, in combination with the shaft furnished with a crank, substantially as and for the purpose specified.
2. The arrangement of the mandrel upon the shaft C, with reference to the anvil B, furnished with grooves *a* in its upper surface, substantially as and for the purpose specified.
3. The supplemental flat-faced anvils A* B* C*, arranged in relation with the main anvil B and the mandrel on the shaft C, substantially as and for the purpose specified.
